UNITED STATES PATENT OFFICE.

EMILE J. GUAY, OF LYNN, MASSACHUSETTS, ASSIGNOR TO GENERAL ELECTRIC COMPANY, A CORPORATION OF NEW YORK.

METAL MIRROR.

Application filed November 24, 1920. Serial No. 426,273.

To all whom it may concern:

Be it known that I, EMILE J. GUAY, a citizen of the United States, residing at Lynn, county of Essex, State of Massachusetts, have invented certain new and useful Improvements in Metal Mirrors, of which the following is a specification.

My invention relates to metal mirrors and the process of making them. More specifically, it relates to silver metal mirrors as distinguished from those mirrors in which silver is also the reflecting medium but which is on the back of a glass body.

An object of my invention is to provide an improved metal mirror, of light weight, which is simple, efficient and rugged and which is readily manufactured.

Another object of my invention is to provide a novel and efficient means of securing the reinforcing material to the mirror.

A further object of my invention is to provide a novel method of making such mirrors, particularly, the method of reinforcing the mirror to maintain its form and prevent dislocation of its focus.

My invention will be better understood from the following description taken in connection with the accompanying drawings and its scope will be pointed out in the appended claims.

In the accompanying drawings illustrating my invention, Fig. 1 is a cross-sectional view of a mirror form with the first steps in the process of manufacturing my mirror indicated thereon; Fig. 2 is an elevation of a part of the perforated mat employed in my process, and Fig. 3 is a cross sectional view similar to Fig. 1 showing a completed mirror on the form.

Referring to the drawings, the numeral 10 indicates a mirror form or pattern made preferably of plate glass, which has been molded to the desired form and then ground and polished on its convex surface. This surface, which determines the shape of the mirror, may be of any suitable type, such as parabolic, hyperbolic or spheroidal, and my invention is not limited to any particular type. However, for purposes of illustration, I have shown a parabolic mirror, which type is more generally used.

As the first step in the manufacture of my mirror, the convex surface of the form is thoroughly cleaned, and is then silvered, either by a chemical deposit or otherwise.

While in practice I have found silver to be the preferred reflecting surface, other metals can be used, and while in the following description I shall speak of silver as the reflecting surface, it is to be understood that any efficiently reflecting metal could take its place. Also while I have found that silver, if such is used as the reflecting medium, can be readily deposited chemically, it may be deposited by spraying it on the glass in a finely divided molten condition, and there are still other ways of depositing a suitable reflecting medium onto the glass form. Consequently, while in the following description I shall mainly speak of chemically deposited silver, it is to be understood that either the silver or other reflecting media need not be deposited chemically.

The deposited silver coating is preferably, although not necessarily, reinforced by an electrolytic deposit of silver. The original silver deposit and the reinforcement are indicated by the numerals 11 and 11' respectively. The particular manner in which the electrolytic deposits are accomplished forms no part of my invention. It may be done in any suitable manner, the preferred method being claimed in a pending application of Cromwell A. B. Halvorson, Jr., Serial No. 364,537, filed March 9, 1920, which application is assigned to the assignee of the present application.

The structure is now reinforced by an electrolytic deposit of copper 13 of the desired thickness. Instead of a deposit of copper, I may produce a deposit of any other suitable metal, notably copper-nickel alloy or of nickel alone; these and other metals would be the equivalents of copper.

After the copper coating 13 has been deposited on the silver coating, a perforated mat 14, preferably of soft rubber, is placed over the copper coating. This mat may be secured to the glass form 10 in any suitable manner, such as by wooden clothes-pins of the spring actuated type. The mat is of a desired thickness, and its perforations 15, are of suitable diameter, preferably about $\frac{1}{32}$ of an inch and fairly close together. The mirror as thus formed with the mat 14 secured in the manner described is now placed in a copper-plating tank until copper has filled the perforations 15, thereby forming on the copper deposit 13 a grid of anchoring studs or pins 16. The electrolytic

2
action is permitted to continue until the copper begins to mushroom through the perforations in the mat, thus forming slight enlargements at the top of the pins 16. The mirror is then taken from the electrolytic bath, and the securing pins and mat removed.

The mirror is now ready for backing to give it the necessary rigidity to prevent any change in its form and consequent displacement of its focus. This backing, indicated by the numeral 17, is made of suitable cement, Portland cement or plaster of Paris, or the like. A suitable adhesive material 15 may be introduced between the backing 17 and the copper 13. The cement is applied to the copper 13 and the spaces between the pins 16 filled in, after which the cement is uniformly applied to cover the pins to a 20 desired thickness. The cement backing 17 is anchored to the copper deposit 13 by the pins 16, in a manner readily understood.

After the cement has been permitted to dry, the mirror is removed from the form 10. 25 This may be accomplished in one of several ways. For example, by the contraction of the cement in hardening, the mirror is more or less loosened from the form 10 and this loosening is promoted either by inserting 30 thin wooden wedges between the mirror and the frame or by tapping the edge of the structure with a rawhide hammer.

When the copper is electrolytically deposited on the silver coating, the contact between the copper and the silver is more than 35 a mere adhesive contact. It is in the nature

of a molecular or chemical contact. The particles on the copper and on the silver have come so close together as to be held together by the atomic forces. In the accompanying claims when the expression "molecular contact" is used, a close contact of this character is intended.

40 While I have described my invention in a specific manner, it should be understood that I do not limit my invention thereto, since various modifications thereof will suggest themselves to those skilled in the art without departing from the spirit of my invention.

50 What I claim as new and desire to secure by Letters Patent of the United States, is:

1. The process of producing a mirror of the desired shape which consists in depositing a reflecting surface on a form of highly polished glass, reinforcing said surface by an electrolytic deposit of copper, electrolytically forming a grid of anchoring pins over the surface of said copper deposit, stiffening the structure so formed by applying a backing of cementitious plastic material to the copper anchored to said pins, and removing the mirror from the form.

55 2. A mirror having an exposed reflecting surface of chemically deposited silver reinforced by an electrolytic backing of copper, a grid of anchoring pins electrolytically formed on said copper backing, and a backing of cement anchored to said pins.

60 In witness whereof, I have hereunto set my hand this 20th day of November, 1920.

70 EMILE J. GUAY.
